MULTIPLE PICK HAMMER

Albert S. Molnar, Valley Stream, N. Y.

Application February 23, 1955, Serial No. 490,081

1 Claim. (Cl. 81—15)

This invention relates to the art of metal working tools and particularly concerns a novel hammer useful in shaping sheet metal structures.

The invention has particular utility in straightening or restoring contours to sheet metal bodies of automobiles, trucks, buses and the like.

It is therefore a principal object to provide a hammer for shaping sheet metal structures.

It is a further object to provide a tool usable in a closely confined space to straighten or shape the contours of a vehicle body structure as desired.

It is a further object to provide a hammer with a multiple pick face and massive head adapted to shape a sheet metal structure without damaging the metal.

Other and further objects and advantages of the invention will become apparent from the following description taken together with the drawing wherein:

Fig. 1 is a side elevational view of a hammer embodying the invention.

Fig. 2 is a front view of the face of the hammer.

Fig. 3 is a sectional view taken on lines 3—3 of Fig. 1.

The hammer shown in the drawing consisting of Figs. 1, 2 and 3 includes a massive hammer head 10 and a relatively light wood handle 11. The handle is wedged at one end into a recess 12 in the hammer head. Head 10 is preferably formed of a one-piece hardened steel member which is drop forged to produce the toughness and ruggedness required in a tool of this character. The head is generally cylindrical but tapers somewhat from the central circumference C to faces 13, 13'. Its diameter is about one and one half inches at the center line C and is substantially as long as its axial length. The front face 13 of the head has a uniform generally spherical convex curvature and is about one and one quarter inches in diameter. Ten truncated conical pick elements 14 are disposed uniformly around the perimeter P of the face. In the forwardly extending central portion of the face 13 are five pick elements 15. A pick element 16 is disposed at the center of the face 13 and protrudes forwardly beyond all the surrounding picks. The pick elements 15 are aligned on spherical radii R with alternate pick elements 14 and with the central element 16. The length of each pick element is substantially three-sixteenths of an inch, and the centers of the apical faces 17 of the several pick elements have a spacing of substantially 0.25 of an inch. The apical faces 17 of all pick elements are disposed parallel to each other with pick elements 14 and 15 coplanar in their respective planes. The axes A of the conical pick elements are all disposed parallel to each other so that each conical pick element 14 and 15 is truncated obliquely at the base where it joins the face 13. This structure and disposition of the several pick elements are important. Since all faces 17 are parallel and face forward, a forwardly facing blow of the hammer on a metal sheet is first struck by pick element 16. Then the blow is distributed among five pick elements 15. The ten pick elements 14 do not contact

2

the metal sheet until the sheet has been bent beyond pick element 15. When contact with pick elements 14 is made the force of the blow is distributed among ten elements. These pick elements 15, 16 serve initially to knock out dents while pick elements 14 prevent undesired stretching of the metal because ten times as much force is required to bend the metal sheet the same distance when pick elements 14 are contacted as when pick element 16 is contacted. Contact with pick elements 15 requires five times the force as for pick element 16 and one half the force for pick elements 14. This controlled application of force prevents undesired stretching of the metal sheet as above mentioned. Furthermore since the several pick elements are disposed on a curved face 13, a picking type blow is struck no matter what the angle of incidence of the blow. A marked reduction in "picking" time is thus accomplished in sheet metal work by use of the present picking hammer embodying the invention.

The parallel arrangement of the axes of the pick elements and the tapered shape of head 10 are important in facilitating the forging operation by which the hammer is fabricated. If the axes were disposed as radii of a sphere, it would not be possible to release the hammer from the recessed forging die. Since the pick elements are all conical and their axes are parallel, and since the head of the hammer tapers toward its ends, said head together with its conical pick elements releases readily from the forging dies.

The head of the hammer is balanced, with its compactly formed massive head and long wood handle to require less swinging space to drive effective blows. Thus in difficult working places such as closed fenders, door panels, hoods, shells, turret tops and the like the hammer is used with ease. In very tight places the smooth contoured head may be held in the palm of the hand and very effective blows can be struck therewith.

Even those comparatively unskilled in performing picking operations on sheet metal structures are enabled to accomplish satisfactory work because of the ready adaptability of the present pick hammer to a limitless variety of picking situations.

Although a single preferred embodiment of the invention has been disclosed it will be apparent to those skilled in the art that many changes are possible without departing from the spirit of the invention as defined by the scope of the appended claim.

I claim:

A multiple pick hammer for shaping sheet metal, comprising a generally cylindrical steel head and a wooden handle attached thereto, one face of said head being convexly curved throughout and carrying a plurality of conical pick elements uniformly spaced on said convex face on a circular line along its perimeter, a second group of conical pick elements uniformly spaced on a circular line spaced inwardly from the first mentioned circular line, and a single conical pick element disposed at the center of said second mentioned circular line, all of said pick elements having axes disposed parallel to each other and being of uniform length so that the free ends of all of said pick elements are so disposed as to present a convex pick-formed striking face on said head.
